Hans Egli, Santa Monica, Calif., assignor to The Garrett Corporation, Los Angeles, Calif., a corporation of California

Filed Apr. 4, 1966, Ser. No. 539,947
16 Claims. (Cl. 253—20)

This invention relates to machines for transferring energy, and more particularly to such machines wherein the energy transfer involves a fluid medium.

This invention is primarily concerned with the transfer of energy either to or from the fluid by a moving member.

This invention is further concerned with fluid handling machines wherein the relative fluid motion upon appropriate active working surfaces accomplishes the transfer of energy.

This invention fits into the general category of other successful fluid handling machines near the rotary and turbomachine category.

The categorization is accomplished by comparing a specific diameter and a specific speed of such fluid handling machines. In such a categorization, the piston type fluid handling machines have relatively large specific diameters and relatively low specific speeds with an efficiency factor approaching 80%. The rotary type machines, such as roots blowers or vane pumps or motors, have much smaller specific diameters and much higher specific speeds than piston type machines, and have an efficiency factor of approximately 60%. The terms "specific diameter" and "specific speed" are used in their well-known meaning to those familiar with the turbine art.

Turbomachines comprise a third broad category of fluid handling machines. They have larger specific speeds than rotary type turbomachines and these turbomachines have an efficiency factor of approximately 80%. Turbomachines, in general, consist of radial, axial and mixed flow types of machines.

This invention provides a fluid handling machine which has a range of specific diameters and specific speeds fitting between the conventional turbomachines and the rotary machines, and overlapping considerably into the category of rotary machines.

This invention occupies a useful application area which previously has been unsuccessfully occupied by fluid handling machines commonly called drag pumps and drag turbines. These prior art fluid handling machines have been characterized by relatively low efficiency factors. The efficiency factor with which these machines have been known to operate has been approximately 40%, with the best alleged performance for a single drag type pump or friction pump, as it is sometimes so referred to, being approximately 50%. However, normal efficiencies of this type of machine are 40% or lower.

This invention provides a fluid handling machine for the transfer of energy, which machine has an efficiency factor of between 65% and 70% with a potential for even better efficiencies over a relatively broad operating range.

This invention has as one of its advantages a much higher peak efficiency. It has a further advantage that it has a sizable region of operating conditions such as speed, flow and pressure ratios over which it will operate with a high efficiency.

A further advantage of this invention is that it will produce for a given tip speed of the active working surfaces a much higher head than prior art machines, wherein head is defined as the energy transfer per pound of fluid. Thus, it becomes obvious that the advantages of this machine are manifold and of much practical importance over comparable prior art machines and that this machine, when compared to other types of turbomachinery, will

2

extend the range of useful fields of applications of turbomachines.

It is yet another advantage of this invention that a high head is obtained within a single stage. Thus, it is possible to utilize a single machine rather than a plurality of stages of conventional machines to obtain the same head.

It is an object of this invention to provide a practical dynamic energy transfer machine with a high rate of energy transfer and a moderate capacity of fluid flow.

It is a still further object of this invention to provide a simple vaneless machine which will transfer energy by forcing the fluid to travel between the active working surfaces of the machine at least twice, as the fluid passes from the inlet to the outlet of the machine.

It is a still further object of this invention to provide an energy transfer machine which has minimal losses within the machine, thereby increasing its efficiency.

It is another object of this invention to provide an energy transfer machine which is economical to manufacture, due to its inherent simplicity.

It is another object of this invention to provide an energy transfer machine wherein the efficiency obtainable is considerably greater than that of any presently known machine having similar specific speeds and specific diameters.

These and other objects of this invention become apparent as the following description is read in conjunction with the drawings in which:

FIG. 1 is a representation of one embodiment of this invention;

FIG. 2 is a sectional view of a plane passing through the line 2—2 of FIG. 1, and

FIGS. 3a and 3b are representations of other embodiments of this invention taken through a section similar to 35 but not taken at section 3—3 of FIG. 1.

Referring now to the drawings, and more specifically to FIG. 1, there is illustrated a plurality of driven means or shafts 10. At least one of these shafts 10 may be connected to a source of energy or to an output, depending upon whether or not the device of FIG. 1 is being used to transfer energy from or to the fluid medium. For purposes of illustration and description of this invention, it will be assumed that this invention is operating as a pump, and therefore at least one of the shafts 10 will be connected to some sort of driving or energy source. This energy source may be of any well-known type, such as a motor.

In FIG. 1 there is also shown an inlet 11 and an outlet 12. It is through this inlet 11 that a source of working fluid is available or is made available to the machine of this invention. The source of the fluid is not shown herein but may be any well-known source of fluid such as a tank of fluid. Further, this fluid will be exhausted to the outlet 12, with the outlet 12 of the machine of this invention connected to a working device to utilize the energy imparted to the fluid by this invention. The machine of this invention also has an inlet passage 13 and an outlet passage 14. These passages provide, in conjunction with the housing means 15, the required guidance for the fluid flowing between the active members 16.

These active members 16 are mounted on a moving means such as a belt 17, which, in a pump, is rotated by the force applied to the shaft or shafts 10. The moving members or active members 16 are transported through the housing means 15 and through two sealed or relatively tight fitting openings 18 during ingress and egress. The housing 15 and the moving active members fit snugly at the points of ingress and egress. The active members 16 are arranged in a cascade fashion, the cascade being in the direction of motion of the active members 16. These active members 16 have a predetermined camber. The fluid enters the inlet 11 and proceeds through the

inlet passage 13. The fluid particles are passed between different ones of the active members 16 and then proceed in a predetermined manner such that substantially all the fluid passes at least a second time between the active members. Due to the snug fit of the inlet and outlet passages, and the housing in relation to the active members at the points of ingress and egress, the fluid is substantially all forced to follow the path shown in FIGS. 1 and 2. The machine of this invention provides for a general fluid energy increase in the direction of motion of the active members. The energy level of the individual fluid particles is increased in the pump means of this invention during each and every passage between the active members prior to entry into the outlet passage. The housing 15 is provided with an aerodynamically smooth surface and is absolutely devoid of any vanes or guiding means within the housing.

The fluid, as it approaches for the first time part of the set of active members 16 at station A—A, has a uniform total energy distribution. The inlet passage 13 and the portion 19 of the housing 15 are shaped in such a fashion that the velocity vector distribution at station A—A is uneven. This velocity vector distribution is required in order that the fluid particles, after their first passage between said active members at station B—B, have a total energy distribution conforming to the general total energy distribution throughout the machine in the direction of motion of the active members.

At the station C—C, immediately prior to the last passage between part of the set of active members 16, the fluid has an uneven total energy distribution. The outlet passage 14 and the portion 20 of the housing 15 are shaped in such a fashion that the fluid particles, after the last passage between said active members, have a substantially uniform total energy level at station D—D. This energy level is essentially maintained throughout the outlet passage 14 until egress from the machine through outlet 12.

The cascaded active members 16 may follow any path between the ingress and egress openings 18. A machine of this invention will always have an ingress and egress opening and the active members, or the cascaded active members, will always pass these openings. If the path of the active members is rotary, then the openings 18 into the housing 15 will be connected.

FIGS. 1 and 2 show a linear motion of the cascade within the machine, whereas FIGS. 3a and 3b show a rotary motion. In FIGURE 3a or 3b the device comprises a single shaft 33 with a rotor disk or arms 34 secured to the shaft. In this embodiment, belt 17, which carries blades 16, is secured to the peripheral edge of the disk 34 or outer ends of the arms 34 and the housing 15 extends around the rotor and is obviously curved rather than elongated.

It is possible to have a shroud means such as the shroud means 31, as shown in FIG. 3a, connected to the active members 16. A shroud means may vary anywhere from a simple shroud performing strictly mechanical functions well known to persons skilled in turbomachinery, to a shroud which performs not only certain mechanical functions but also performs additional functions within the concepts of this invention.

The additional function which a shroud means such as that shown in FIG. 3a performs is the assistance of the walls of the housing 15 in directing the fluid with a minimum of internal losses as the fluid flows from the inlet 11 to the outlet 12. The efficiency of the machine of this invention is improved with the addition of the shroud means 31, as shown in FIG. 3a, or of the separate stationary means 32, as shown in FIG. 3b. This stationary means 32 also may vary in shape. As shown in FIG. 3b, this inner stationary member 32 is completely disposed within the space bound by the inner surface of the housing 15. The housing 15 and the inner member, whether it be a shroud 31 or a separate member 32, form a passage

geometry which directs the flow of the fluid to yield a minimum of separation and losses in the fluid. The inner wall, or surface of the housing 15, and the inlet and outlet passages and the shroud means 31, or the separate member means 32, all co-operate in directing the fluid with minimum losses throughout the machine.

It is noted in the FIGS. 1 and 2 that the active members 16 are arranged in a cascade fashion. This cascade is in the direction of motion of the active members 16 as they pass through the housing 15. The active members 16 may be arranged at any position on the periphery of the channel cross section as shown in FIG. 3a or 3b of the housing 15 in a plane perpendicular to the direction of motion of the active members. However, with given shapes of channel cross sections, there exists a position on the periphery where the fluid approaches a majority of these active members along the cascade at a constant angle of incidence over a wide operating range of the machine. The angle of incidence is preferably small. Each active member thus works within its optimum operating region. As the position of the active members 16 on the periphery is varied, the limits of practical incidence variation over the operating range of the machine may be controlled. If compressible fluids are used in the machine of this invention, the passage area may diminish in the direction of the increased fluid density. Such changes in the passage area are well known to those skilled in the turbomachinery art.

As is illustrated in FIGS. 3a and 3b, the projected area of these active members 16 in a plane perpendicular to the direction of motion of the active members 16 is less than the projected area of the remainder of the flow channel in the housing means 15. The machine does not operate most efficiently if the remainder of the flow channel area in the housing is less than the projected area of the active members 16 in the plane perpendicular to the direction of their motion.

Active members 16 have a predetermined configuration. These active members 16 are normally of an air foil type shape and have an appropriate camber line with a thickness distribution superimposed on the camber line. Active members having a flat surface will not produce an efficient machine.

It will be apparent to those skilled in the art that the novel principles of the invention disclosed herein will suggest various other modifications and applications of the same. It is accordingly desired that the present invention shall not be limited to the specific embodiment thereof described herein.

What is claimed is:

1. A machine for transferring energy comprising:
inlet means, said inlet means connected to a source of working fluid;
an inlet passage;
outlet means, said outlet means for discharging said working fluid;
an outlet passage;
vaneless housing means connecting said inlet means and said outlet means;
  2. A machine for transferring energy comprising:
inlet means, said inlet means connected to a source of working fluid;
an inlet passage;
outlet means, said outlet means for discharging said working fluid;
- 55
- 60
- 65
- 70
- 75

- an outlet passage;
vaneless housing means connecting said inlet passage and said outlet passage;
- a plurality of active members, said active members mounted as a set on a moving means whereby said active members continuously traverse through said housing and past said inlet passage and said outlet passage, said active members including a shroud means, substantially all of said fluid forced to pass at least twice between said active members in its travel between said inlet and said outlet whereby energy is transferred between said fluid and said active members. 5
3. A machine for transferring energy comprising:
inlet means, said inlet means connected to a source of working fluid;
an inlet passage;
outlet means, said outlet means for discharging said working fluid;
an outlet passage; 20
vaneless housing means connecting said inlet passage and said outlet passage;
a plurality of active members, said active members mounted as a set on a moving means whereby said active members continuously traverse through said housing and past said inlet passage and said outlet passage, said active members including a shroud means, said shroud means formed so as to guide the flow of said working fluid, substantially all of said fluid passing at least twice between said active members in the travel of the fluid between said inlet and said outlet whereby energy is transferred between said fluid and said active members. 25
4. A machine for transferring energy comprising:
inlet means, said inlet means connected to a source of working fluid; 35
an inlet passage for guiding said working fluid;
outlet means, said outlet means for discharging said fluid from a housing;
an outlet passage, said outlet passage guiding said fluid from said housing; 40
vaneless housing means connecting said inlet passage and said outlet passage, said housing means including a plurality of surfaces, said fluid contained between said surfaces; 45
- a plurality of substantially identical active members, said active members mounted on means for moving said members, said active members moving past said inlet passage and said outlet passage and through said housing means; 50
said fluid passing at least twice between said active members during the transfer of said fluid between said inlet and said outlet whereby energy is transferred between said fluid and said active members. 55
5. A machine for transferring energy comprising:
inlet means, said inlet means comprising an inlet and a passage connected to a source of working fluid, said passage guiding said working fluid; 60
outlet means, said outlet means comprising a passage for discharging said fluid from a housing, said outlet passage guiding said fluid from said housing in a predetermined manner;
vaneless housing means connecting said inlet means and said outlet means, said housing means including a plurality of surfaces, said housing surfaces including inner and outer surfaces defining a channel for the movement of said fluid between said inlet passage and said outlet passage; 65
- a plurality of substantially identical active members, said active members mounted on means for moving said members, said active members moving past said inlet passage and said outlet passage through said housing means, said fluid passing at least twice between said active members in the travel of said fluid between said inlet and said outlet whereby energy is transferred between said fluid and said active members. 70

- is transferred between said fluid and said active members.
6. A machine for transferring energy comprising:
inlet means, said inlet means comprising an inlet and a passage connected to a source of working fluid, said passage guiding said working fluid in a predetermined manner;
outlet means, said outlet means comprising an outlet and a passage for discharging said fluid from a housing, said outlet passage guiding said fluid from said housing in a predetermined manner;
vaneless housing means connecting said inlet means and said outlet means, said housing means including a plurality of surfaces, said surfaces including inner and outer surfaces defining a continuous channel for movement of said fluid between said inlet and said outlet, said inner surface comprising a member disposed within the space bound by said outer surface;
- a plurality of substantially identical active members, said active members mounted on means for moving said members, said active members moving past said inlet passage and said outlet passage and through the walls of said housing means; said fluid passing at least twice between said active members in the travel of said fluid between said inlet and said outlet whereby energy is transferred between said fluid and said active members. 75
7. A machine for transferring energy comprising:
inlet means, said inlet means comprising an inlet and a passage connected to a source of working fluid, said passage guiding said working fluid in a predetermined manner;
outlet means, said outlet means comprising an outlet and a passage for discharging said fluid from a housing, said outlet passage guiding said fluid from said housing in a predetermined manner;
vaneless housing means connecting said inlet means and said outlet means, said housing means including a plurality of surfaces, said housing surfaces including inner and outer surfaces, said inner surface comprising a member disposed within the space bound by that outer surface;
- a plurality of substantially identical active members, said active members mounted on means for moving said members, said identical members arranged in a cascade fashion in the direction of motion of said active members, said active members passing said inlet passage and said outlet passage and through the walls of said housing means; 80
said active members transferring said fluid between said inlet and said outlet passages, substantially all of said fluid forced to pass at least twice between said active members in the travel of said fluid between said inlet and said outlet, whereby energy is transferred between said fluid and said active members.
8. A machine for transferring energy comprising:
inlet means, said inlet means comprising an inlet and a passage connected to a source of working fluid, said passage guiding said working fluid to a plurality of active members, said fluid having an uneven velocity vector distribution such that after the first passage of said fluid between said active members the total energy distribution of said fluid is varied in the same manner as the general fluid energy distribution in the direction of motion of said active members;
- outlet means, said outlet means comprising an outlet and a passage for discharging said fluid from said housing;
- vaneless housing means connecting said inlet means and said outlet means;
- a plurality of substantially identical active members, said active members mounted on means for moving

said active members, said identical members arranged in a cascade fashion in the direction of motion of said active members, said active members moving past said inlet passage and said outlet passage and through said housing means, said active members including a shroud means, said shroud means and said surface acting to direct the flow of said working fluid whereby substantially all of said fluid is forced to pass at least twice in the same direction between said active members in the travel of said fluid between said inlet and said outlet whereby energy is transferred between said fluid and said active members.

9. A machine for transferring energy comprising:

inlet means, said inlet means comprising an inlet and at least one passage connected to a source of working fluid, said passage guiding said working fluid to a plurality of active members with said fluid having an uneven velocity vector distribution prior to passing through said active members such that after the first passage of said fluid between said active members the distribution of total energy in said fluid is varied in the same manner as the general fluid energy distribution in the direction of motion of said active members;

outlet means, said outlet means comprising an outlet and at least one passage for discharging said fluid from said machine, said outlet passage influencing said fluid upstream of the last passage of said fluid through said active members whereby the particles of said working fluid within the fluid stream have a substantially uniform energy level upon egress;

vaneless housing means connecting said inlet means and said outlet means, said housing means including a plurality of surfaces, a plurality of substantially identical active members, said active members mounted on means for moving said active members, said identical active members arranged in a cascade fashion in the direction of motion of said active members, said active members moving past said inlet passage and said outlet passage and through said housing means; said surfaces directing the flow of substantially all of said fluid whereby said fluid is forced to pass at least twice between said active members in the travel of said fluid between said inlet and said outlet whereby energy is transferred between said fluid and said active members.

10. A machine for transferring energy comprising:

inlet means, said inlet means comprising an inlet and at least one passage connected to a source of working fluid, said passage guiding said working fluid to a plurality of active members whereby said fluid has an uneven velocity vector distribution prior to passing through said active members such that after the first passage of said fluid between said active members the distribution of total energy in said fluid is varied in the same manner as the general fluid energy distribution in the direction of motion of said active members;

outlet means, said outlet means comprising an outlet and at least one passage for discharging said fluid from said machine, said outlet passage influencing said fluid upstream of the last passage of said fluid through said active members whereby the particles of said working fluid within the fluid stream have a substantially uniform energy level upon egress;

vaneless housing means connecting said inlet means and said outlet means, said housing means including at least one surface; a plurality of substantially identical active members, said active members mounted on means for moving said active members, said identical members arranged in a cascade fashion in the direction of motion of said active members whereby said active members are moved past said inlet passage,

said outlet passage and through said housing means, said active members including a shroud means; said surface and said active members defining such a channel for the movement of said fluid between said inlet and said outlet whereby substantially all of said fluid is forced to pass at least twice in the same direction between said active members in the travel of the fluid between said inlet and said outlet means whereby energy is transferred between said fluid and said active members.

11. The machine for transferring energy of claim 10 in which said surface and said active members act upon said working fluid whereby the particles of fluid traverse at least twice around the inner member in the advance of said fluid particles between said inlet and said outlet means.

12. The machine for transferring energy as defined in claim 10, wherein the housing surface and the shroud surface of said active members are shaped and positioned relative to each other to form a passage geometry having a mean shape whereby the flow separation of and losses in said fluid are substantially minimized.

13. A machine for transferring energy comprising:
inlet means, said inlet means comprising an inlet and at least one passage connected to a source of working fluid, said passage guiding said working fluid to a plurality of active members with said fluid having an uneven velocity vector distribution prior to passing said active members such that after the first passage of said fluid between said active members the distribution of total energy in said fluid is varied in the same manner as the general fluid energy distribution in the direction of motion of said active members; outlet means, said outlet means comprising an outlet and at least one passage for discharging said fluid from said machine, said outlet passage influencing said fluid upstream of the last passage of said fluid through said active members whereby the particles of said working fluid within the fluid stream have a substantially uniform energy level upon egress;

vaneless housing means connecting said inlet means and said outlet means, said housing means including a plurality of surfaces; a plurality of substantially identical active members, said active members mounted in a cascade fashion in the direction of motion of said active members on means for moving said active members, said active members moved past said inlet passage, said outlet passage and through at least one surface of said housing means; said surfaces including inner and outer surfaces defining a channel for the movement of said fluid between said inlet and said outlet means, said surface and said active members acting on said working fluid whereby the particles of fluid traverse a path repeatedly around the inner surface and through said active members as said fluid advances from said inlet means to said outlet means, said inner and said outer surfaces being shaped and positioned relative to each other to form a passage geometry having such a mean shape that the flow separation of or losses in said fluid are substantially minimized, substantially all of said fluid passing at least twice in the same direction between said active members in the travel of said fluid between said inlet means and said outlet means whereby energy is transferred between said fluid and said active members.

14. The machine for transferring energy of claim 13 in which said active members are arranged with relation to the periphery of the cross section in a plane perpendicular to the direction of motion of said active members whereby said fluid approaches a majority of the active members along the cascade at a constant angle of incidence.

15. The machine for transferring energy of claim 13 in which the projected area of said active members in a

plane perpendicular to the direction of motion of said active members always being less than the projected area of the remainder of said channel in said plane.

16. The machine for transferring energy of claim 13, wherein said active members have a thickness configuration of an air foil, said thickness configuration superimposed on the camber line to produce substantially zero incidence between said fluid and said active members.
